UNITED STATES PATENT OFFICE.

JOHN R. FLINN, OF JOHNSTOWN, PENNSYLVANIA.

GARBAGE-CAN.

1,351,747.

Specification of Letters Patent. Patented Sept. 7, 1920.

Application filed December 4, 1918. Serial No. 265,210.

To all whom it may concern:

Be it known that I, JOHN R. FLINN, a citizen of the United States, residing at Johnstown, in the county of Cambria and State of Pennsylvania, have invented certain new and useful Improvements in Garbage-Cans, of which the following is a specification.

This invention relates to garbage cans and aims principally to increase the longevity 10 of the can and to attain a maximum degree of sanitation.

A further object of the invention is to utilize the standard type of garbage can and to equip it with parts which will fulfil 15 the above objects, without materially increasing even the initial cost of the can.

Other objects of the invention will be in part described and in part understood from the following description taken in connection 20 with the accompanying drawings in which:—

Figure 1 is a vertical sectional view of a garbage can constructed in accordance with my invention.

25 Fig. 2 is a perspective view of the centering ring used in my invention, and

Fig. 3 is a detail fragmentary perspective view of the inner receptacle showing to advantage one of the handles.

30 In the drawings a receptacle 1 is shown which is preferably of a cylindrical configuration of any desired height. The receptacle is provided with a lid 2 which may likewise be of any desired form.

35 Mounted in the receptacle 1 is a skeleton annulus or ring 3 which rests on the bottom of the receptacle and has its outer periphery in snug engagement with the inner periphery of the receptacle. A plurality of

40 fingers 4 are arranged on the inner periphery of said ring, each finger consisting of an elastic strap one end of which is secured adjacent the outer margin of the ring and the opposite end flexed downwardly, the 45 point of flexure being substantially coincident with the upper margin of said ring. It will be noted that the fingers are arranged at diametrically opposite points.

An inner receptacle 5 is mounted in the receptacle 1 said inner receptacle being likewise of a cylindrical configuration and of a diameter slightly lesser than diameter of the receptacle 1. The bottom 6 of the inner receptacle 5 is of conical configuration, and is 55 adapted to seat on the fingers 4. By making the bottom of conical form, it will be

appreciated that centering of the inner receptacle will be greatly facilitated. A coordinate function of this formation of bottom is to insure complete dispensing of the 60 contents of the receptacle when the latter is tilted for emptying the contents into a depository, such as a wagon usually provided for the purpose of carrying away refuse. It will be seen that by this construction of 65 bottom that adherence of the contents of the receptacle, especially at the junction of the bottom with the body of the receptacle, will be reduced to a minimum.

A pair of handles 7 are hingedly mounted 70 on the inner periphery of the inner receptacle 5 in proximity to the outer terminal of the latter. The handles are so arranged as to normally lie completely within the inner receptacle, although when the contents 75 of the latter is to be dispensed the handles may be turned outwardly into the position indicated by dotted lines in Fig. 3 to permit grasping the same at a point above the outer terminal of said inner receptacle.

The relative sizes of the inner and outer receptacles are such that a comparatively small space will be provided between the receptacles, in order to prevent, as far as possible, refuse from dropping therebetween 85 However, if perchance garbage should become lodged between receptacles, or in the bottom of the outer receptacle the latter may be very readily cleaned out, especially in view of the fact that ring 3 is removable. 90 Moreover if desired the outer receptacle 1 may be used as a container for a deodorant.

Various changes in the details of construction, proportion and arrangement of the parts set forth in the above invention may 95 be made without departing from the spirit and scope of the appended claims.

What is claimed is:—

1. A garbage can including an outer receptacle equipped with a detachable ring 100 embracing the inner periphery of the latter, an inner receptacle for concentric mounting in said outer receptacle and ring, and fingers carried by said ring and engaging the inner receptacle to retain the latter centered. 105

2. A garbage can including an outer receptacle, a ring arranged on the bottom of said receptacle, a plurality of resilient straps, one end of each of which is secured to the inner periphery of said ring and the 110 opposite end bent inwardly, an inner receptacle having a conical bottom to engage the

free ends of said straps, substantially as set forth.

3. A garbage can including an outer receptacle, an inner receptacle, and an annulus mounted in the outer receptacle and equipped with inwardly extending inclined fingers to bear against the bottom of the inner receptacle for centering the latter.

4. A garbage can including an outer receptacle, an annulus mounted in said receptacle having inclined yielding fingers, an inner receptacle having a conical bottom engageable with said fingers, and a lid covering both receptacles. 10

In testimony whereof I affix my signature. 15
JOHN R. FLINN.
